9 Claims. (Cl. 230—143)

A screw rotor machine for elastic working fluid is a machine which primarily comprises at least two coplanar, cooperating rotors provided with helical lands with a wrap angle of less than 360° and intervening grooves, and a housing enclosing the rotors. The rotors are of male and female type which means that the lands of the male rotors have at least their major portions outside the pitch circle of the rotor and have substantially convex flanks, and that the lands of the female rotor have at least their major portions inside the pitch circle of the rotor and have substantially concave flanks. The housing enclosing the rotors is further provided with a working space substantially composed of two coplanar intermeshing bores, each sealingly enclosing a rotor, and provided with spaced low pressure and high pressure ports, of which at least their major portions are located, respectively, on opposite sides of the plane of the axes of the bores.

The rotors cooperate in such a way that a land of one rotor meshes with a groove of the cooperating rotor on the same side of the plane of the axes of the bores as the high pressure port is located whereby a chevron-shaped chamber is formed between the rotors and the walls of the working space comprising a portion of a male rotor groove and a portion of a female rotor groove communicating therewith. Each such chamber has its base ends located in a stationary transverse plane common for all chevron-shaped chambers and located at the high pressure port and its tip at the intermesh between the rotor lands of the different rotors. When the rotors revolve the tip of the chevron-shaped chamber is then moved axially in relation to the stationary plane so that the volume of the chamber is varied.

By variation of the shape of the ports, especially that of the high pressure port, the ratio between the volumes of the chevron-shaped chambers at the moment when the communication with the ports is broken and opened, respectively, the built-in volume ratio can be varied. In this way the ratio between the pressures in the chevron-shaped chambers at said moment, the built-in pressure ratio, can also be varied. The built-in pressure ratio is, however, in addition to the built-in volume ratio also dependent on the ratio between the specific heats at constant pressure and at constant volume, respectively, the κ -value, of the used elastic working fluid. This κ -value varies between different gases which means that the built-in pressure ratio is different in one and the same machine in dependence on the gas used as working fluid.

One problem in a screw rotor machine of the type mentioned above is that the pressure within a chevron-shaped chamber is not uniformly distributed. In a compressor the pressure is thus highest at the tip of the chamber where pressure initiation takes place due to the penetration of the land of the cooperating rotor into the groove. The pressure thus initiated is then transmitted within the groove in the direction towards the end of the rotor. In the same way though not so accentuated the pressure is lower near the leading groove flank than near the trailing groove flank as the gas enclosed in the groove is transported in circumferential direction as the rotors revolve. For this reason the gas enclosed in the groove is

2

in a continuous movement in relation to the flanks of the groove.

When the chamber is opened towards the high pressure port the pressure distribution in the groove is thus such that the pressure in certain portions thereof is higher than the pressure in the port while in other portions it is lower than that in the port. The flow between the groove and the high pressure port will then at the portions of the groove in which there is an excess pressure in relation to the high pressure port be in the direction from the groove to the port and at the portions of the groove in which there is a pressure lower than that in the high pressure port in the direction from the port to the groove. These flows cause an ununiform pressure distribution in the port resulting in turbulence and noise. Of course the flow conditions change due to the pressure equalization in the groove taking place during the continued revolving of the rotors. For each opening of a chamber towards the port there is thus a periodic course resulting in an oscillation having a frequency coinciding with the number of the chevron-shaped chambers formed and opening towards the port per time unit, i.e. coinciding with the product of the number of revolutions of the rotor and the number of grooves in the rotor.

25 The flows in different directions arising when the chevron shaped chambers open towards the high pressure port cause an abrupt decrease of the driving torque demanded by this chamber as the outflow from the pressure initiating zone is facilitated due to the sudden increase of the outflow area therefrom so that the initiating pressure decreases and as the pressure especially on the leading groove flanks increases. The changes in the driving torque caused in this way are so large that under certain circumstances they cause a change of direction of the torque acting on the female rotor, the driving torque of which normally is only a fraction of the corresponding torque of the male rotor, which means that the continuous driving contact between the elements transmitting torque to the female rotor is broken and results in strong clearly noticeable vibrations of the female rotor.

If these torque transmitting elements are the flank surfaces of the male and female rotor lands the wear of the cooperating flanks is considerably increased.

On the other hand, if these torque transmitting elements are a synchronizing gearing connecting the male and female rotors these vibrations can produce within the female rotor and especially within its shaft portion carrying the synchronizing gear secondary vibrations substantially of torsional type of such an amplitude that seizing between the rotors and corresponding wear takes place. In such a way complete breakdowns of the rotors have occurred with synchronized as well as with unsynchronized rotors.

The present invention has for its object to solve this oscillation problem which, as stated above, substantially emanates from the pressure variations in the high pressure port and the invention is based on the fact that it has been established by tests that no oscillations of the mentioned type occur at a certain distribution of the driving torque of the machine between two cooperating male and female rotors.

By analysis of the frequencies of the noise existing in the outlet channel of a compressor and caused by pressure oscillations, which noise has a sound level of about 150 decibels, it has proved that most of the noise has a frequency corresponding to the number per time unit of emptied chevron shaped chamber, i.e. the product of the number of revolution of a rotor per time unit and the number of lands of the rotor, or frequencies corresponding to harmonics thereof, which proves that the pressure variations produced in a compressor outlet are of a considerable magnitude.

In the standard profile (embodying the symmetrical

circular profile disclosed in U.S. Patent No. 2,622,787) hitherto used the rotors have the same outer diameters and the male rotor is provided with four lands and the female rotor with six lands. Each female rotor groove consists, when viewed in a transverse plane, of an inner portion limited by the pitch circle of the rotor and a circular arc having its centre on the pitch circle and a radius which is 18% of the outer diameter of the rotor, and of an outer portion limited by the circumscribing circle and the pitch circle of the rotor and by addenda to the rotor lands limiting the groove said addenda being located outside the pitch circle and having a radial extent corresponding to 14.3% of the length of the chord to the pitch circle lying within the land separating two adjacent grooves.

With this standard profile theoretically about 6.7% of the driving power is transmitted to the female rotor which owing to the speed ratio between the rotors means that the magnitude of the torque of the female rotor is about 11% of the magnitude of the corresponding torque of the male rotor. By increasing the radial addendum of the female rotor its torque may be increased so that at for instance an addendum having a radial extent corresponding to 20% of said chord about 9.5% of the driving power is transmitted to the female rotor, i.e. the magnitude of the torque of the female rotor is increased to about 17% of the magnitude of the corresponding torque of the male rotor. At the same time the displacement volume of the machine increases with about 3.5% which is also favourable.

However, an increase of the radial addendum of the female rotor also results in effects of undesirable nature so that the magnitude of the addendum must be limited and only for special applications can be increased to such a magnitude as is shown for instance in the aforesaid Patent No. 2,622,787 where the addendum is completely circular which means an addendum having a radial extent of about 50% of said chord involving that almost 24% of the power is transmitted to the female rotor the torque of which will be about 46% of the corresponding torque of the male rotor. The reason for this is among others that the blow hole between two adjacent chevron shaped chambers caused by the addendum will be too large in relation to the volume of said chambers. Thus, the flow through the blow holes results in that the pressure in all chevron shaped chambers is about equal to the pressure in the high pressure port of the machine which means a considerable decrease of the efficiency of the machine. Further, the increase of the power transmission to the female rotor means an increased risk of wear of the rotors especially in machines without synchronizing gears. Tests have shown that a completely circular addendum brings about such a decrease of the efficiency that such addenda cannot be used in practice but in special types of machines where the characteristics obtained by combination effects balance the decrease of the efficiency. A type of machine in which the circular addendum for this reason is used is a two stage tandem compressor where it is essential to bring about so large differences between the displacement volumes of the first and the second stage that a pressure distribution between the stages can be obtained which is most favourable as regards efficiency. Such a machine is shown in U.S. Patent 2,975,963.

In machines having a synchronizing gearing an increase of the power transmission to the female rotor involves that the torque acting on the journal shafts carrying the synchronizing gears and thus the risk of torsional deformation of said shafts increases which in turn increases the risk of seizing between the rotors.

It has, therefore, been found suitable to shape the rotors in such a way that the radial extent of the addenda of the female rotors lies within the range 18 to 37.5% of said chord which results in an increase of the torque of the female rotor in relation to said standard profile by 25 to 160% and a maximum increase of the blow hole by about 50% in relation to the standard profile. This

may be compared with the 50% addendum suggested in the aforesaid U.S. Patent No. 2,622,787 which causes an increase of the blow hole by about 100% in relation to that of the standard profile. It has proved that an optimum of the radial extent of the addendum lies within the range 20 to 30% of the chord which gives an increase of the torque of the female rotor by 40 to 110% and a maximum increase of the blow hole by about 33% in relation to the standard profile. With respect to the shape of the corresponding rotor and the housing it has been found especially suitable to give the addendum a radial extent of about 25% to the length of the chord which means an increase of the torque of the female rotor by about 75% while the increase of the blow hole is kept below 25% in relation to that of the standard profile.

It has also proved that the risk of oscillations decreases with increase of the built-in pressure ratio, i.e. with one and the same working fluid at a decrease of the area of the land flanks exposed to the pressure variations in the high pressure port, in other words, the magnitude of the variations of the torque of the female rotor deriving therefrom in relation to the driving torque transmitted between the rotors.

In practice it has thus proved that screw rotor machines with rotors of standard profile operate perfectly without vibrations as compressors with a built-in pressure ratio of about 7:1 which is used within a very important field, viz. for producing compressed air for pneumatic tools and the like which normally work at a pressure of about 7 kg./cm.².

The main fields for screw rotor machines, however, require considerably lower built-in pressure ratios.

For compression of gases where it is of importance that the gas must not be polluted by liquid, screw compressors are used which operate dry without injection of cooling liquid into the working space. In such machines the practical upper limit of the built-in pressure ratio is about 5:1 owing to the thermal deformation of the rotors and the housing in spite of the most intense cooling possible of the rotors and the housing by a cooling fluid completely separated from the working fluid and passing through cooling channels.

Another important field for screw compressors is that for compression of a cooling medium, especially for air conditioning plants. Compressors for this purpose are normally owing to the desired condensing and evaporating temperature designed for a built-in pressure ratio of about 3:1 and usually for a built-in pressure ratio not exceeding 5:1.

In practical use it has appeared that vibrations of the mentioned type arise in screw rotor machines designed for the built-in pressure ratios actual in the fields mentioned above and provided with rotors of standard profile. This is true for machines operating dry as well as for machines with oil injection into the working space. It has thus been necessary in order on the whole to bring machines of these types to function mechanically to provide them with synchronizing gearings connecting the rotors. Owing to the risk of seizing between the rotors and damages of the rotors arising therefrom the clearances between the rotors must be dimensioned under consideration of the angular deviations of the female rotor from the synchronized position due to the arising vibrations. This means that it has been necessary to make the clearances larger than if no vibrations in the rotors had occurred.

Tests have shown, however, that it is possible to prevent the generation of such vibrations in the female rotor also with built-in pressure ratios lying below 5:1 by modifying the rotor profiles and thus the distribution of the torque between the rotors in such a way that the torque of the female rotor is proportionally increased. By elimination of such vibrations in the female rotor there is thus a possibility to reduce the clearances between the rotors while maintaining mechanical reliability in opera-

tion and to obtain a reduction of the leakage losses within the machine which manifests itself by an increased efficiency of the machine. This means that the screw rotor machine obtains an increased capacity of competition with other known types of machines used for the same purposes. At least in machines with oil injection into the working space the advantage is furthermore obtained that the torque can be transmitted between the rotors by direct flank contact which thus means an elimination of the synchronizing gearing and the costs therefor in connection with manufacture and adjustment at service as well as at the manufacture of new machines which further influences the capacity of competition of the machine in a favourable way.

In the following part of the specification the invention will be described in detail in connection with a number of suitable embodiments of the screw rotor machine shown in the drawings.

FIG. 1 shows a vertical section through a screw rotor compressor along the line 1—1 in FIG. 2.

FIG. 2 shows a cross section of the compressor shown in FIG. 1 along the line 2—2 in FIG. 1.

FIG. 3 shows another cross section of the compressor shown in FIG. 1 along the line 3—3 in FIG. 1.

FIG. 4 shows a horizontal section of the compressor shown in FIG. 1 with the rotors removed, the section being taken along the line 4—4 in FIG. 1.

FIG. 5 is a diagram showing the volume of a chamber when opening against the high pressure port plotted against the axial extent of the high pressure port.

FIG. 6 shows the cross section of a pair of cooperating rotors mounted in the machine.

FIG. 6a shows on a larger scale the addendum of a female rotor land located outside the pitch circle of the rotor.

FIG. 6b shows on a larger scale the dedendum at the bottom of a male rotor groove located inside the pitch circle of the rotor.

FIG. 7 shows a vertical section through another screw compressor according to the invention.

FIG. 8 shows a vertical section through a third screw compressor according to the invention.

The screw compressor shown in FIGS. 1 to 4 comprises a casing 10, in which a working space 12 is provided in the shape of two intersecting cylindrical bores with parallel axes. The casing 10 is further provided with a low pressure channel 14 and a high pressure channel 16 for the working fluid which communicate with the working space 12 through the low pressure port 18 and the high pressure port 20, respectively.

In the shown compressor the low pressure port 18 is located entirely in the low pressure end wall 22 of the working space 12 and substantially on one side of the plane containing the axes of the bores (FIG. 2). In the shown compressor the high pressure port 20 is located partly in the high pressure end wall 24 and partly in the barrel wall 26 of the working space 12 and entirely on the side of the plane containing the axes of the bores opposite to the low pressure port (FIGS. 3 and 4).

In the working space 12 two cooperating rotors, one male rotor 28 and one female rotor 30, are located with their axes coaxial with the axes of the bores. The rotors are journaled in the casing 10 but for the sake of simplicity the bearings carrying the rotors are omitted. The rotors 28, 30 are further connected through a synchronizing gear 32 of the gear wheel type. The male rotor 28 is provided with an external shaft 34 projecting from the casing 10.

The male rotor 28 is provided with four helical lands 36 with intervening grooves 38 which have a wrap angle of about 300°. The female rotor 30 is provided with six helical lands 40 with intervening grooves 42 which have a wrap angle of about 200°. As shown in FIG. 6 the flanks of the male rotor lands 36 are composed of three main portions, viz. an outer portion between the points 44

and 46 which at full intermesh between the male rotor land 36 and a female rotor groove lies inside the pitch circle 48 of the female rotor and which, when viewed in a transverse plane, is substantially circular around a centre located on the pitch circle 50 of the male rotor with a radius which is 18.7% of the outer diameter of the male rotor, an intermediate portion between the points 46 and 52 located between said outer portion and the pitch circle 50 of the male motor, said intermediate portion being generated by a point 54 on the flank of the female rotor groove 42 located at the pitch circle 48 of the female rotor, and an inner portion between the points 52 and 56 located inside the pitch circle 50 of the male rotor the shape of which will be clear from the following portion of the specification. The flanks of the female rotor lands 40 are correspondingly composed of two different portions, viz. an inner portion between the points 58 and 54 located inside the pitch circle 48 of the female rotor and circular around a centre located on the pitch circle 48 of the female rotor with a radius which is 18.7% of the outer diameter of the female rotor, and an outer portion between the points 54 and 60 located outside the pitch circle 48 of the female rotor with a radial extent 62—60 the length of which is about 25.4% of the length of the chord to the pitch circle 48 of the female rotor lying within a female rotor land 40 and the end points of which are the point 54 and an equally located point 64 on an adjacent female rotor land flank. The inner portion 52—56 of the male rotor land flank is shaped in such a way that it continuously seals against the outer portion 54—60 of the female rotor land flank, when said portion passes into or out of the dedendum of the male rotor groove 38 lying inside the pitch circle 50 of the rotor. In order to make it possible to use smaller clearances between the tips 44, 60 of the rotor lands and the barrel wall 26 of the casing and in this way to get a decreased leakage the tips of the rotor lands are shaped in such a way that the male rotor land 36 is slightly cut away on both sides of its outermost portion 44 so that only a thin sealing edge is left, and the radially outermost portion 60 of the addendum of the female rotor land 40 is also shaped as a thin sealing edge, a corresponding groove being provided at the innermost portion 56 of the bottom of the male rotor groove 38.

Thus the female rotor has lands with profiles consisting of circular portions lying inside the pitch circle of the rotor with addendum portions connecting the circular portions and lying outside the pitch circle of the rotor, and the male rotor has grooves with profiles having circular portions lying outside the pitch circle of the rotor connected by dedendum portions at the bottoms of the grooves complementary in shape to the addendum portions of the female rotor lands.

The low pressure port 18 is so shaped that the rotor grooves communicating therewith are open over their whole length when the communication is broken so that the complete displacement volume of the machine is always utilized. The high pressure port 20 which as said above comprises a portion located in the high pressure end wall 24 and a portion located in the barrel wall 26 is, however, shaped in such a way that the rotor grooves 38, 42 when they start to communicate with the high pressure port 20 have a considerably smaller volume than that corresponding to completely open grooves. The high pressure port 20 is shaped in such a way that its edges in the barrel wall 26 as well as in the high pressure end wall are substantially parallel with the portions of the lands limiting the grooves when the communication with the grooves commences. In order to define the size of the high pressure port it is sufficient to speak only about the position of the point 66 where the edge of the barrel wall sealing against the tip of the male rotor land 36 crosses the intersection line between the two bores of the working space 12 as the size of the high pressure port is distinctly defined thereby. The determining factor is the distance

of the point 66 from the low pressure end wall as is clearly shown in the diagram of FIG. 5 where the volume of the groove portions forming a discharging chevron shaped chamber expressed in percentage of the total volume of the two grooves is shown as a function of the distance from the low pressure end wall of the point 66 expressed in percentage of the total distance between the low pressure and high pressure end walls.

The ratio of the total volume of the grooves to the volume of the chevron shaped chamber when opening against the high pressure port is called the built-in volume ratio of the machine, ϵ . The mean pressure in the chevron shaped chamber when it opens against the high pressure port can be calculated by means of the built-in volume ratio and the κ -value of the working fluid defined already in the introduction to the specification. The ratio of the mean pressure in the chevron shaped chamber when it opens against the high pressure port to the pressure in the grooves completely filled by working fluid when communicating with the low pressure port, the built-in pressure ratio π_i can thus be calculated from the formula

$$\pi_i = \epsilon^*$$

The machine operates in the following way. The rotors are rotated by a motor (not shown) through the shaft 34 projecting from the casing 34 and through the synchronizing gear 32 connecting the rotors. Working fluid is sucked in through the low pressure channel 14 and the low pressure port 18 into the working space 12 where it flows into the portions of the rotor grooves 38, 42 which are open against the low pressure port 18 so that the grooves are filled with working fluid to their whole length. The working fluid is then moved circumferentially by the rotors. During this movement a female rotor land 40 first enters the male rotor groove 38 and a male rotor land 36 then also enters the female rotor groove 42. In this way a chevron shaped chamber composed of two communicating grooves is formed which is sealed against the high pressure port 20 as well as against the low pressure port 18 and the volume of which continuously decreases during the rotation of the rotors. During this decrease of the volume the pressure in the chamber increases in the first hand at the intermesh between a land and the cooperating groove. The pressure initiated in this way is then transmitted through the rotor grooves in the direction towards the high pressure ends of the rotors. Owing to the rotation of the rotors a composed axial and circumferential movement is imparted to the mass of working fluid enclosed in each groove where the axial component dominates near to the apex of the chevron shaped chamber and the circumferential component dominates near to the base of the chevron shaped chamber. In this way there is a higher pressure in the working fluid adjacent to the driving trailing flank of the rotor then adjacent to the leading flank of the rotor. The pressure distribution within a chevron shaped chamber is thus very ununiform but becomes more and more uniform as the rotors revolve and the pressure wave from the intermesh is transmitted from the apex towards the base of the chevron shaped chamber. In working fluids in which the velocity of sound is relatively high this pressure transmission also occurs faster than in working fluids in which the velocity of sound is relatively low. After a certain rotation of the rotors corresponding to a predetermined turning angle of the male rotor the chevron shaped chamber is opened towards the high pressure port. The pressure distribution within the chevron shaped chamber is then still ununiform so that the pressure in the portion thereof located most adjacent to the apex of the chamber is higher than the pressure in the high pressure channel while the pressure in other portions of the chamber more adjacent to its base is lower than that in the high pressure channel. Owing to this fact a flow condition composed of different partial flows in opposite directions arises when the chamber opens

against the high pressure port. Owing to the high pressure close to the apex of the chamber and the sudden increase in the out flow area threfrom a substantial flow arises in this portion of the high pressure port in the direction from the chamber to the high pressure channel so that the pressure in said portion of the chamber decreases which results in an immediate reduction of the power with which the rotors act on the working fluid, i.e. a rapid decrease of the torque necessary for rotating the rotors. At the same time a flow arises in the portion of the port which is closest to the base of the chevron shaped chamber in the direction from the high pressure channel to the grooves so that the pressure in the grooves increases rapidly to the same level as the pressure in the channel. In this way the pressure in the grooves increases especially adjacent to the leading flanks which causes a push trying to drive the rotors forwardly with a higher speed than that at which they normally rotate. Also in this way a rapid decrease of the torque necessary for rotating the rotors is obtained. The total decrease of the torque thus obtained may lead to that the female rotor for a moment is driven by the gas instead of driving the gas if the female rotor has such a profile that its power transmission is below a certain percentage of the total power transmission. When the rotors continue their rotation the pressure in the grooves is rapidly equalized except for the zone closest to the intermesh from where, however, the out flow area is so large that the pressure at this point does not at all reach the same level as if the intermesh point had still been covered by barrel walls surrounding the rotors. The working fluid flows in this way from the working space 12 through the high pressure port 20 to the high pressure channel 16 and from there out from the machine.

Owing to the above flow conditions there is a periodic variation of the torque load of the rotors which variation has a frequency which corresponds to the number of chevron shaped chambers opening to the high pressure port per time unit or, in other words, the product of the number of revolutions of the rotor and the number of the lands of the rotor. By shaping the profiles of the rotors in accordance with the invention it is guaranteed that the torque driving the female rotor forward is greater than the decrease thereof arising when a chamber opens to the high pressure port, whereby it is avoided that the rotor is subjected to an acceleration at this moment causing vibrations of the rotor.

The compressor shown in FIG. 7 differs from the one shown in FIG. 1 only by the fact that the synchronizing gear 32 connecting the rotors has been omitted so that the torque transmission between the rotors is obtained by direct flank contact therebetween.

The compressor shown in FIG. 8 differs from the one shown in FIG. 1 only by the fact that the synchronizing gear 32 connecting the rotors has been omitted so that the torque transmission between the rotors is obtained by direct flank contact therebetween, and by the fact that the compressor is provided with openings 68 in the casing 10 for injection under pressure of a liquid supplied from a pressure liquid source, not shown, close to the intersection line between the bores of the working space 12 on the same side of the plane of the axes of the bores as the high pressure port 20, whereby on one hand an improved cooling and sealing is obtained within the compressor and on the other a liquid film is obtained on the rotor flanks contacting each other.

The invention is of course not limited to the embodiments shown but comprises everything falling within the scope of the following claims.

What I claim is:

1. A screw rotor machine for elastic working fluid comprising two coplanar intermeshing male and female rotors having helical lands with a wrap angle of less than 360° and intervening grooves and a casing enclosing said

rotors in sealing relationship to provide working space for the fluid, said lands having profiles comprising substantially circular portions on the male flanks lying outside the pitch circle of the male rotor and substantially circular portions on the female flanks lying inside the pitch circle of the female rotor, each of the lands of the female rotor further having an addendum portion extending outside the pitch circle of the female rotor, the radial extent of said addendum being within the range of from 18% to 37.5% of the length of the chord of the portion of the pitch circle of the female rotor lying within the land and the bottom portion of each of the grooves of the male rotor having a dedendum portion lying inside the pitch circle of the male rotor and having a profile complementary to that of said addendum portions of the female rotor land.

2. A screw rotor machine as defined in claim 1, in which the radial extent of the addendum portions of the female rotor lands is within the range of from 20% to 30% of the length of said chord.

3. A screw rotor machine as defined in claim 2, in which the radial extent of said dedendum portion is approximately 25% of the length of said chord.

4. A screw rotor machine as defined in claim 3, in which the male rotor has four lands and the female rotor has six lands with intervening grooves and in which the portion of each female rotor groove located inside the pitch circle of the rotor has a profile comprised by a circular arc having its center on the pitch circle of the female rotor and a radius the length of which is approximately 18.7% of the outer diameter of the rotor, whereby to provide male and female rotors of approximately the same outer diameter.

5. A screw rotor machine as defined in claim 1 in which the rotors and the high and low pressure ports communicating with the working space are so formed and dimensioned in relation to each other that the built-in pressure ratio for the elastic working fluid is less than 5 to 1.

6. For use in a screw rotor machine of the character described, a pair of cooperating rotors, comprising a male rotor and a female rotor having helical lands with a wrap

angle of less than 360° and intervening grooves, said lands having profiles comprising substantially circular flank portions on the male flanks lying outside the pitch circle of the male rotor and substantially circular portions on the female flanks lying inside the pitch circle of the female rotor, each of the lands of the female rotor further having an addendum portion extending outside the pitch circle of the female rotor, the radial extent of said addendum portion being within the range of from 18% to 37.5% of the length of the chord of the portion of the pitch circle of the female rotor lying within the land and the bottom portion of each of the grooves of the male rotor having a dedendum portion lying inside the pitch circle of the male rotor and having a profile complementary to that of said addendum portions of the female rotor lands.

7. Rotors as defined in claim 6 in which the radial extent of said addendum portions is within the range of from 20% to 30% of the length of said chord.

8. Rotors as defined in claim 7 in which the radial extent of said addendum portions is approximately 25% of the length of said chord.

9. Rotors as defined in claim 8 in which the male rotor has four lands and the female rotor has six lands with intervening grooves and the portions of the female rotor grooves lying inside the pitch circle of the female rotor are defined by profiles comprised of circular arcs having their centers on the pitch circle of the female rotor and a radius the length of which is approximately 18.7% of the outer diameter of the female rotor.
